UNITED STATES PATENT OFFICE.

PETER T. GRAVES, OF MILWAUKEE, WISCONSIN, ASSIGNOR TO THE
MILWAUKEE CHAIR COMPANY, OF SAME PLACE.

STOOL.

SPECIFICATION forming part of Letters Patent No. 339,165, dated April 6, 1886.

Application filed August 24, 1885. Serial No. 175,180. (No model.)

To all whom it may concern:

Be it known that I, PETER T. GRAVES, of Milwaukee, in the county of Milwaukee and State of Wisconsin, have invented new and useful Improvements in Stools; and I do hereby declare the following to be a full, clear, and exact description of said invention, reference being had to the accompanying drawings, and to the letters or figures of reference marked thereon, which form a part of this specification.

My invention, to be hereinafter distinctly claimed, relates to a stool provided with a foot-rest.

15 In the accompanying drawings, Figure 1 is a perspective view of the complete stool. Fig. 2 is a section, with portions broken away, showing some of the interior parts.

In the stool shown in the drawings the legs 20 *a a a a* are made of bent wood, the top ends being secured in a metal cap, *b*, having sockets in its under side, into which the ends of the legs are fitted, and in which they are retained by means of screws passing through the top of the cap and screwed into the ends of the legs. 25 These legs diverge from each other downwardly, so that at the bottom the legs are far enough apart to cause the stool to stand firmly and to provide against its being too easily over-turned. At a distance up from the lower ends 30 of the legs *a a a* a brace-block, *c*, is inserted between the legs, against which the legs bear, and which holds the legs apart. Staying-rods *d d*, each furnished with a head at one end 35 and with a screw-thread and nut at the other end, are inserted horizontally through two opposite legs and through the intervening brace-block, *c*, whereby the brace-block is held in position, and the legs are drawn toward 40 each other and are held firmly in position against the block *c*.

Heretofore in a work-stand a ring has been used to which the legs on each side were connected by short bolts, as shown in Letters Patent of the United States No. 138,072, issued 45 to C. S. Caple, April 22, 1873; and in an office-stool rods have been used for braces, as shown in Letters Patent of the United States No. 275,384, issued to M. V. B. Howe on April 10,

1883, which devices, as there shown and described, I do not claim as my invention.

About the legs, at a distance from the lower extremities, is the foot-rest *e*, supported at a distance from the legs on the brackets *f f*, the lower ends of which brackets are made rigid 55 to the legs *a*.

The foot-rest *e* and the brackets *f f* are also preferably constructed of bent wood, and the lower ends of the brackets are preferably placed over and so secured to the legs *a a* as to 60 cover and hide from sight the end of the rods *d d*.

Heretofore a foot-rest affixed directly to the legs has been used, as shown in the patent to Howe, above mentioned; but such a form of 65 construction is not adapted for use with a stool built as mine is, having legs near together from near their top to near their lower extremities, for a rest so constructed and attached directly to the legs would be too small 70 and too much obstructed by the legs for convenient use, and such a construction would not so well cover the ends of the staying-rods, nor be so ornate in appearance as the construction adopted in my stool. The seat *g* is provided on its under side with a rigid downwardly-projecting screw, *h*, which turns in a corresponding screw-thread in an aperture in the center of the cap *b*, whereby said seat is 75 adjustable up or down.

I do not wish to confine my form of stool to those having only four legs, as a stool having the distinctive features of my invention may be constructed with three or any greater number of legs.

What I claim as new, and desire to secure by Letters Patent, is—

1. In a stool, the combination of the legs *a*, the brace-block *c*, the outer edge of which is in contact with the legs, and the staying-rods *d d*, each of which rods passes through two legs, and through the intervening staying-block, *c*, substantially as described.

2. In a stool, the combination of the legs *a*, brackets *f f*, rigid on the legs *a*, and an enclosing foot-rest, *e*, supported on the brackets at a distance from the legs, substantially as described.

3. In a stool, the combination of the legs *a*, the staying - rods *d*, and the brackets *f*, said brackets being so located and attached to the legs as to cover and hide the ends of the staying- rods, substantially as described.

4. In a stool, the combination of the legs *a*, brace-block *c*, the outer edge of which block is against the legs *a*, rods *d*, each passing through two legs and the intervening block, *c*, with the brackets *f*, rigid on the legs *a*, and

the encompassing foot-rest *e*, supported at a distance from the legs on the brackets, substantially as set forth.

In testimony whereof I affix my signature in presence of two witnesses.

PETER T. GRAVES.
